UNITED STATES PATENT OFFICE.

CARROLL KNOWLES, OF HARTFORD, CONNECTICUT, ASSIGNOR TO PRATT & WHITNEY COMPANY, OF NEW YORK, N. Y., A CORPORATION OF NEW JERSEY.

BACK REST FOR CYLINDRICAL GRINDERS.

Application filed September 17, 1923, Serial No. 663,159. Renewed May 12, 1926.

This invention relates to an improved form of work rest or support adapted to be applied to a grinding machine for operating upon cylindrical work and adapted to be 5 automatically actuated during the operation of the machine.

A principal object of the present invention is to provide a rotatably mounted back rest adapted to engage and support cylindrical work substantially opposite to the position of the wheel while it is being ground. Also, it is an object to provide means resiliently forcing the rotatable back rest against the work while the work is being reduced in 15 diameter.

Another object of the invention is to adapt the back rest for use in an automatic grinding machine in which the abrasive wheel is automatically advanced to a predetermined 20 final position and then automatically returned to its initial position after the grinding operation has been completed. While the wheel is being returned to its initial or retracted position, the back rest is momentarily withdrawn from its position against the work to permit a new blank to be positioned for operation on the work supporting and rotating means.

Another object is to provide adjustable 30 means controlling the movements of the back rest so that the support may be trued to advance to its work supporting position after the wheel has contacted with and trued up the work.

I accomplish the above objects by oscillating a member by a cam operated slide 35 controlling the position of the wheel. On this oscillating member which is in the form of a frame is the rotatable back rest.

Another feature of the invention is that I provide a pivoted lever, preferably within 40 the base of the machine, one end of which bears against a lever for actuating the back rest, the other end of the lever being in the path of movement of the supplemental means on the wheel actuating slide.

Another object of the invention is to provide simple connecting means between the actuating slide for the wheel and the oscillating frame of the back rest so that movements 45 of the actuating slide will control the movements of the back rest in proper timed relation to the movements of the wheel. Preferably, and as shown and described in the present application, the frame for the back

rest is resiliently forced forward toward its final operative position and positively withdrawn therefrom by the connections from the actuating slide.

The present construction is of the same 60 general type as the machine shown in my co-pending application Serial No. 580,268, filed August 7, 1922. Particularly, objects of the present invention comprise improvements in the form of back rest and also improved 65 means for actuating it in connection with a full automatic cylindrical grinding machine.

With these and other objects in view, my invention consists in the features of construction and operation set forth in the following 70 specification and illustrated in the accompanying drawings.

In the accompanying drawings annexed hereto and forming a part of this specification, I have shown my invention embodied 75 in a full automatic cylindrical grinding machine for valve stems, but it will be understood that the invention can be otherwise embodied and that the drawings are not to be construed as defining or limiting the scope 80 of the invention, the claims appended to this specification being relied upon for that purpose.

In the drawings:

Figure 1 is a side elevation of a portion of 85 a cylindrical grinding machine showing the improved form of back rest in its operative position.

Fig. 2 is a rear elevation of the same showing the actuating means for the wheel slide 90 and back rest.

Fig. 3 is a front elevation of the work rotating and supporting mechanism shown upon a smaller scale than in Figs. 1 and 2, the back rest being also shown associated 95 therewith, and

Fig. 4 is a fragmentary section on line 4-4 of Fig. 1 showing the mechanism for actuating the back rest in operative relation to the wheel and work.

In the above mentioned drawings, I have shown but one embodiment of the invention which is now deemed preferable, but it is to be understood that changes and modifications may be made within the scope of the 105 appended claims without departing from the spirit of the invention.

Briefly, my invention, in its broadest aspect, comprises the following principal parts: first, a base having a headstock and 110

a tailstock thereon adapted to support and rotate cylindrical work to be ground; second, a rotatable abrasive wheel mounted upon a suitable slide or head; third, a slide 5 movable longitudinally of the machine and having a cam surface for moving the wheel and its slide directly toward or from the work; fourth, a rotatably mounted back rest resiliently forced toward a position to engage the work during operation; fifth, a lever adapted to contact with the wheel slide actuating member and adapted to oscillate a frame carrying the back rest out of engagement with the work when the wheel and wheel slide are in retracted position.

Referring more in detail to the figures of the drawings, I provide a support 10, this support being adapted to be adjustably secured to the work supporting table 11 by means of bolts 12 or other suitable fastening means. Mounted to oscillate upon the support about the axis of a shaft 13 is a frame 14 carrying a rotatably mounted back rest 15. As the support 10 and oscillating frame 14 are generally similar to and operate in the same manner as those described in my copending application Serial No. 580,268, it will be unnecessary to repeat the detailed description thereof. On the forward portion of the oscillating frame or member 14 is the rotatable back rest 15 journaled in an adjustable carrier 16, the position of which may be varied relative to the frame 14 by means of suitable screws 17.

Also mounted on the support 10 is an adjustable stop 18 adapted to contact with a bearing surface 19 provided on the oscillating frame 14. By adjustment of this stop 18, the frame 14 with its back rest 15 may be advanced to any predetermined precise position relative to the work W. Also, to advance the oscillating frame 14 toward the work and to constantly urge it toward its final operative position, a spring pressed plunger 20 is mounted in the support 10, one end of the plunger 20 being adapted to bear against a plate 21 provided on the oscillating frame 14. By adjustment of a screw 22, the tension on an actuating spring 23 bearing against the plunger 20 may be varied to increase or decrease the pressure urging the work rest 15 into contact against the work W.

As shown most clearly in Fig. 1, the oscillating frame 14 supports the rotatable back rest 15 in a position directly opposite to the position of the wheel 25. In this position of the back rest 15, the pressure of the abrasive wheel 25 against the work W is directly taken by the back rest.

Also, as shown in Fig. 1, the wheel 25 is mounted rotatably in a slide 26 movable toward and from the work W. This slide 26 and its actuating means are similar in every way to the corresponding parts shown in my

application Serial No. 587,158, filed September 9, 1922. For that reason, a detailed description will be unnecessary. A drum 27 having cam strips 28 thereon is engaged by a roller 29 on an actuating slide 30 and serves to reciprocate the actuating slide as the drum rotates. A roller 31 on the wheel slide 26 engages a cam slot (not shown) in the actuating slide 30 so that as the actuating slide 30 is reciprocated, the wheel 25 and its slide 26 are advanced and retracted.

In order to retract the work rest 15 from its operative position simultaneously with movements of the wheel 25 away from the work W, the following mechanism is provided: At one end of the shaft 13 about which the frame 14 carrying the work rest oscillates is a short lever 35. This is fastened to the shaft 13 so that movement of the lever 35 will serve to vary the position of the work rest 15 toward or from the work W.

Attached directly to the wheel actuating slide 30 is a rod 36 fastened preferably at one end and extending directly therefrom. On this shaft or rod 36 is a cam plate 37 as shown most clearly in Fig. 2. Movement of the plate 37 with movements of this rod 36 and slide 30 brings a cam surface 38 on the plate 37 into contact with a roller 39 on a lever 40 adapted to oscillate about a shaft 41 mounted within the machine base. In order to time the support 15 to move into work supporting position, the cam plate 37 on the rod 36 is adjustably secured thereto by clamping bolts 42 so that the position of the cam 37 may be varied. By these means, the support 15 when adjusted will be held from contacting with and supporting the work until the wheel has engaged and trued the work. As soon as this takes place, the support 15 may be allowed to advance under the influence of spring 23.

Also the opposite end of the lever 40 which contacts with a surface on the lever 35 to actuate the oscillating frame 14 is provided with an adjustable end 44 preferably threaded thereto so that the length of this lever may be slightly varied. By adjustment of these members including the cam plate 37 and lever 40, the point in the cycle of operations at which the work rest 15 is retracted from the work W also may be slightly varied.

In operation, the work W is mounted upon suitable rotating and supporting means provided on a headstock 50 and tailstock 51. These, as shown, are mounted on the work table 11. The wheel 25 on its slide 26 is positioned for operation on work of varying diameters by adjustment of a screw 52 preferably by means of a hand wheel 53. With the parts properly adjusted the back rest 15 may be accurately adjusted by positioning the stop 18.

The work W may be positioned on its supporting and rotating means by any suitable

means either automatically or manually and the wheel advanced directly toward the work W by the cam controlled means above described. Simultaneously with the advancing movement of the wheel, the work rest 15 will be permitted to advance and support the work while it is being reduced in diameter. During this period of the machine's operation, the roller 39 is away from the 10 cam plate 37 so that spring 23 forces the oscillating frame 14 and the rest 15 toward the work W.

As soon as the operation on one work blank is completed and the wheel 25 is retracted to its initial position away from the work, the slide 30 moves to the right as seen in Fig. 2 and the roller 39 contacts with the cam surface 38 of cam plate 37. This depresses roller 39, oscillates lever 40, and 20 forces the lever end 44 against lever 35 thus retracting the rest 15 from the work W. As long as the slide 30 is in this position so that the roller 39 rests on the cam plate 37, the rest 15 will be held in its retracted position. 25 With the next advancing movement of the wheel slide 26 and corresponding movement of the slide 30, roller 39 passes off the cam plate 37 and thus again permits the rest 15 to advance toward the work. By varying 30 the position of cam plate 37 on the bar 36, the time at which the support 15 is allowed to engage the work is under accurate control. This may be timed to take place only after the wheel 25 has contacted with and ground 35 off any eccentricity of the work.

What I claim is:

1. A cylindrical grinding machine comprising in combination, a base, work supporting and rotating means thereon, a wheel 40 movable toward and from the work, a rotatably mounted back rest adapted to contact with and support the work in operative position during the grinding operation, and means to withdraw the back rest from its operative position when said wheel is moved from the work.

2. A cylindrical grinding machine comprising in combination, a base, work supporting and rotating means thereon, a wheel 50 movable toward and from the work, a rotatably mounted back rest adapted to contact with and support the work in operative position during the grinding operation, and cam actuated means to oscillate the back rest 55 from its operative position when said wheel is moved from the work.

3. A cylindrical grinding machine comprising in combination, a base, work supporting and rotating means thereon, a wheel 60 movable toward and from the work, a rotatably mounted back rest positioned directly opposite the wheel and adapted to contact with and support the work in operative position during the grinding operation, and 65 means to withdraw the back rest from its

operative position when said wheel is moved from the work.

4. A cylindrical grinding machine comprising in combination, a base, work supporting and rotating means thereon, a wheel 70 movable toward and from the work, a cam actuated slide for controlling the position of said wheel, a rotatably mounted back rest adapted to contact with and support the work in its operative position during the grinding operation, and means associated with said cam actuated slide to withdraw the back rest from its operative position when said wheel is moved away from the work.

5. A cylindrical grinding machine comprising in combination, a base, work supporting and rotating means thereon, a wheel 75 movable toward and from the work, a cam actuated slide for controlling the position of said wheel, a rotatably mounted back rest adapted to contact with and support the work in its operative position during the grinding operation, and a lever actuated by said cam actuated slide to withdraw the back rest from its operative position when said wheel is moved away from the work.

6. A cylindrical grinding machine comprising in combination, a base, work supporting and rotating means thereon, a wheel 80 movable toward and from the work, a cam actuated slide for controlling the position of said wheel, a rotatably mounted back rest adapted to contact with and support the work in its operative position during the grinding operation, and a supplementary cam associated with said cam actuated slide and adapted to withdraw the back rest from its operative position when said wheel is moved away from the work.

7. A cylindrical grinding machine comprising in combination, a base, work supporting and rotating means thereon, a wheel 85 movable toward and from the work, a rotatably mounted back rest adapted to contact with and support work in its operative position during the grinding operation, an oscillating frame carrying said back rest, and means to oscillate the frame to retract the back rest from operative position when said wheel is moved away from the work.

8. A cylindrical grinding machine comprising in combination, a base, work supporting and rotating means thereon, a wheel 90 movable toward and from the work, cam actuated means to move said wheel toward and from the work, a rotatably mounted back rest adapted to contact with and support work in its operative position during the grinding operation, an oscillating frame carrying said back rest, and means operated by said cam actuated means to oscillate the frame to retract the back rest from operative position when said wheel is moved away from the work.

9. A cylindrical grinding machine comprising in combination, a base, work supporting and rotating means thereon, a wheel movable toward and from the work, a rotatably mounted back rest adapted to contact with and support work in its operative position during the grinding operation, an oscillating frame carrying said back rest, means to oscillate said frame to retract the back rest from operative position when said wheel is moved away from the work, and resilient means normally forcing said back rest toward its operative position.

10. A cylindrical grinding machine comprising in combination, a base, work supporting and rotating means thereon, a wheel movable toward and from the work, a slide for controlling the position of said wheel, a rotatably mounted back rest adapted to contact with and support work in its operative position during the grinding operation, an oscillating frame carrying the said back rest, and means associated with said slide to oscillate the frame and retract the back rest from operative position when said wheel is moved away from the work.

11. A cylindrical grinding machine comprising in combination, a base, work supporting and rotating means thereon, a wheel movable toward and from the work, a slide for controlling the position of said wheel, a rotatably mounted back rest adapted to contact with and support work in its operative position during the grinding operation, an oscillating frame carrying the said back rest, and a supplemental cam carried by said slide

to oscillate the frame and retract the back rest from operative position when said wheel is moved away from the work.

12. A cylindrical grinding machine comprising in combination, a base, work supporting and rotating means thereon, a wheel movable toward and from the work, a slide for controlling the position of said wheel, a rotatably mounted back rest adapted to contact with and support work in its operative position during the grinding operation, an oscillating frame carrying the said back rest, and a supplemental cam adjustable relative to said slide to oscillate the frame and to retract the back rest from operative position when said wheel is moved away from the work.

13. A cylindrical grinding machine comprising in combination, a base, work supporting and rotating means thereon, a wheel movable toward and from the work, a slide for controlling the position of said wheel, a rotatably mounted back rest adapted to contact with and support work in its operative position during the grinding operation, an oscillating frame carrying the said back rest, a supplemental cam adjustable relative to said slide to oscillate the frame and to retract the back rest from operative position when said wheel is moved away from the work, and resilient means normally forcing said back rest toward its operative position.

In testimony whereof, I hereto affix my signature.

CARROLL KNOWLES.
